DESIGN FOR A REFRESHMENT STAND

Minnie Cuccio, Los Angeles, Calif.

Application January 12, 1935, Serial No. 54,822

Term of patent 7 years

To all whom it may concern:

Be it known that I, Minnie Cuccio, a citizen of the United States, residing at Los Angeles, in the county of Los Angeles and State of California, have invented a new, original, and ornamental Design for a Refreshment Stand, of which the following is a specification, reference being had to the accompanying drawing, forming a part thereof.

Fig. 1 is a front elevational view of the refreshment stand showing my new design; and

Fig. 2 is a transverse cross-sectional view taken through lines 2—2 of Fig. 1.

My invention relates to a refreshment stand

and more particularly to the arrangement of the refreshment stand in form of a barrel, comprising a large barrel surrounded by a circle of small barrels. The large barrel is placed in the center, having its walls arranged to receive a plurality of small barrels the ends of which protrude therethrough and the circle of small barrels comprise a support for the counter and flag poles of the canopy.

I claim:

The ornamental design for a refreshment stand, as shown and described.

MINNIE CUCCIO.
